UNITED STATES PATENT OFFICE.

SAMUEL A. BURNS, OF WEST MERIDEN, CONNECTICUT.

IMPROVEMENT IN DRAWER-PULLS.

Specification forming part of Letters Patent No. 175,025, dated March 21, 1876; application filed March 2, 1876.

To all whom it may concern:

Be it known that I, SAMUEL A. BURNS, of West Meriden, in the county of New Haven and State of Connecticut, have invented a new Improvement in Drawer-Pulls; and I do hereby declare the following, when taken in connection with the accompanying drawings and the letters of reference marked thereon, to be a full, clear, and exact description of the same, and which said drawings constitute part of this specification, and represent, in—

Figure 1, side view; Fig. 2, front view; Figs. 3, 4, 5, detached views of the socket; Figs. 6, 7, detached views of the ball and knob spindle.

This invention relates to an improvement in that class of drawer-pulls in which the knob is hung to a socket by a ball-joint, the object being to simplify the construction of such articles by producing the parts in sheet metal instead of cast, whereby the labor of finishing is to a great extent dispensed with; and the first part of the invention consists in forming a socket and its shank in two longitudinal divisions, each division struck from sheet metal, and forming one-half of the socket and shank, and joined together to complete the shank; and the second part of the invention consists in the ball and knob spindle, also struck complete from a single piece of sheet metal.

a is the socket; *b*, the shank, with a shoulder, *c*, between. The socket is spherical-shaped, with an opening at its front end, and a slot, *d*, upon the lower side, through which the knob-spindle plays. This socket and its shank are formed in two parts, Figs. 4 and 5, making a longitudinal division. Each half is struck into a like form from sheet metal, and the two brought together edge to edge, and soldered or otherwise secured together. This avoids the independent union of the socket and the shank, as in previous sheet-metal constructions, and also avoids the labor necessary to finish a sheet-metal socket.

The internal screw-thread may be stamped into the shank, as indicated, whereby the cutting of the thread is also avoided; but this is not an essential part of the invention, as the thread may be cut.

Instead of soldering the two parts entirely, or to strengthen the connection, a sleeve, *e*, may be set on over the shank, as seen in Fig. 3.

The ball and spindle are formed from a single piece of sheet metal struck into form, as seen in Fig. 6, by means of dies. This forms a semi-spherical ball, *f*, with its neck *g*, shoulder *h*, and spindle *i*. In striking into this form the open side will be equal to the diameter; but the width of the metal is sufficient to make a complete cylinder, or nearly so, of the spindle *i*, and in striking it into shape, as seen in Fig. 6, the screw-thread on the spindle is formed in the same dies, and after the part has been thus shaped it is completed by closing the edges of the spindle *i*, and bringing it into cylindrical form, as seen in Fig. 7, which completes the part. The thread, however, may be cut upon the spindle, if desired. The ball may be placed within the socket before the two parts are united, and retained there by its form corresponding to that of the socket, or a pintle may be passed through both socket and ball to secure them in position. The open side of the ball being inward, only the full form of the ball is exposed, as seen in Fig. 2.

I claim—

1. The socket for drawer-pull, consisting of the socket *a*, shoulder *c*, and shank *b*, formed in two longitudinal parts, and united substantially as described.

2. The ball and spindle of a drawer-pull, formed complete in a single piece of sheet metal, substantially as described.

SAMUEL A. BURNS.
